UNITED STATES PATENT OFFICE.

EDWARD R. WHARTON, OF MEDFORD, MASSACHUSETTS.

FOLDABLE WATERPROOF BOOT.

Application filed November 26, 1926. Serial No. 150,829.

This invention relates to a foot and leg covering, formed to cover the foot and the calf portion of the leg of the wearer, and constituting a high boot.

5 The chief object of the invention is to provide a high boot of light weight, adapted to be compactly folded, so that it may be conveniently stored in a receptacle, such as a hand bag, and of such construction that 10 when in use, it will present a neat and attractive appearance, enhanced by the fact that portions of the stocking are visible.

Of the accompanying drawings forming a part of this specification—

15 Figure 1 shows in perspective a boot embodying the invention, as it appears when in use, a portion of the outer leg layer being broken away.

Figure 2 is a side view of one of the sections constituting the inner leg layer.

Figure 3 is a side view of one of the sections constituting the outer leg layer.

Figure 4 is a section on line 4—4 of Figure 1.

25 Figure 5 is a section on line 5—5 of Figure 1.

Figure 6 is a side view, showing the bottom portion differently formed.

The same reference characters indicate 30 the same parts in all of the figures.

My improved boot comprises a waterproof bottom portion including a wear-sustaining sole and a wear-sustaining upper member. As shown by Figures 1 and 2, the sole includes a fore part 12, a shank part 13, and a heel part 14. The upper member 15 is 35

35 standing, or projects upward from the sole, as in a rubber overshoe, and may be very narrow or low, as shown by Figures 1 and 5, or considerably wider, or higher, as shown by 40 Figure 6. In each case, the bottom member constitutes, in effect, a rubber overshoe which is of the extremely low-cut type in Figures 1 and 5, and of the high-cut type in Figure 6. The sole and upper members 45 may be constructed and united as usual in rubber overshoes.

To the upper member 15 is connected by a 50 waterproof seam or joint formed in any suitable way, an outer leg layer 16, of thin, limp and transparent waterproof sheet material, preferably China silk, a well known material used in the manufacture of rain coats or slickers. This layer may be composed of two pieces or sections, each formed 55 as shown by Figure 3, or otherwise formed, the sections being so joined to each other

and to the upper member 15 of the bottom portion, that a boot is provided having a water-excluding external surface formed in 6 part on the bottom portion, and in part on the outer layer 16. The bottom portion and the outer layer constitute a foot and leg covering, the entire external surfaces of which are impervious to water. The leg layer 16, 65 when made of material such as China silk, is too limp to constitute, without reinforcement, a leg which is satisfactory in respects other than imperviousness to water, so that I reinforce it by the inner leg layer next 70 described.

The reinforcing inner layer designated by 75 17, is composed of material of greater strength and stiffness than China silk, and is preferably of textile fabric, although it may be of thin leather, or any other suitable material. Said layer is of openwork construction, its continuity being interrupted by openings 17^a the form and arrangement of which are such that the layer is adapted to 80 be collapsed by folding or rolling, into smaller compass, than would be possible if the layer were continuous or uninterrupted.

The openings also permit the color of a 85 stocking to be seen through the transparent China silk, when the boot is in use, the attractiveness of the boot being thus enhanced.

The inner layer may be composed of two 90 pieces or sections, each formed as shown by Figure 2, although they may be otherwise formed. The inner layer may be joined to the outer layer and joined, with the latter, to the upper member 15, by any suitable means, so that the leg formed by the two layers is securely connected with the bottom portion, and the inner layer is caused to 95 reinforce the limp outer layer and cause it to conform closely to the portions of the limb which it covers.

The openwork inner layer may be produced by either cutting the openings 17^a 100 out of a section of continuous cloth, or by sewing together strips of tape, or other suitable material, the strips extending in different directions and being arranged to bound the openings 17.

The sections forming the outer and inner layers may be united by a butted vertical seam 19 (Figure 4) at the rear side of the laminated leg. The seam may be 110 covered by a stay strip 19^a. The customary opening which permits the opening of the leg and the closing thereof by a lacing, or other closing means, may have its opposite

edges formed by the longitudinal forward edges of the sections of which the layers are composed. Said forward edges may be perforated to receive eyelets 20, engaging a lacing 21, and may be additionally reinforced to support the eyelets, if desired.

The laminated leg above described is adapted to be folded wrapped or roller around the bottom portion, which includes the sole and the upper member 15. The openwork or skeleton form of the inner layer, and the thinness and limpness of the outer layer, enable the boot to be reduced to a flattened roll of such small size that it may be conveniently packed in a hand bag. The well known transparency of the China silk enables portions of a stocking within the leg to be seen through the openings 17^a. The outer layer may be stitched to the openwork inner layer by lines 22 of stitches, indicated conventionally by Figures 1 and 6.

The longitudinal leg opening may be closed by a tongue 23, when the boot is in use, the tongue being suitably secured and adapted to extend across the opening and overlap the inner side portions of the leg at opposite sides of the opening. The tongue may include an inner layer of flexible leather and an outer layer of China silk, matching the outer leg layer.

The joining of the lower end of the leg to the upper member 15 may be effected by

applying a tape binding 25 (Figure 5) to the lower end of the leg, cementing the binding to the layers 16 and 17, cementing the outer side of the binding to the upper member 15, and sewing together the member 15, the binding, and the layers, by stitches 26.

I claim:

A foldable waterproof boot, comprising a waterproof bottom portion including a wear-sustaining sole and heel, and a wear-sustaining upper member upstanding therefrom, an outer leg layer of thin and limp transparent waterproof sheet material, having a waterproof connection with the upper member, so that the boot has a water-excluding external surface in part on the bottom portion, and in part on the outer layer, and a flexible reinforcing inner leg layer joined to the upper member and to the outer layer, the inner layer being of openwork construction, so that it has sight openings and may be compactly folded, and composed of material of greater strength and stiffness than that of the outer layer, so that when the boot is in use, the outer layer is reinforced and supported by the inner layer, with portions of the stocking visible, the leg formed by said layers being adapted to be folded compactly around the bottom portion for storage.

In testimony whereof I have affixed my signature.

EDWARD R. WHARTON.
